DESIGN FOR A LIGHTING FIXTURE

Edward E. Ashley, Darien, Conn., and Alexander E. Blumenthal, Pittsburgh, Pa., assignors of one-third to Kaufmann & Baer Company, a corporation of Pennsylvania, also doing business as Gimbel Bros., Pittsburgh, Pa.

Application May 8, 1941, Serial No. 100,848

Term of patent 14 years

To all whom it may concern:

Be it known that we, Edward E. Ashley, a citizen of the United States, residing in Noroton Heights, Darien, in the county of Fairfield, State of Connecticut, and Alexander E. Blumenthal, a citizen of the United States, residing in Pittsburgh, in the county of Allegheny, State of Pennsylvania, have invented a new, original, and ornamental Design for a Lighting Fixture, of which the following is a specification, reference being had to the accompanying drawing, forming a part thereof.

In the drawing Fig. 1 is a plan view of a lighting fixture showing our new design; Figs. 2 and 3 are side and end views, respectively, thereof; and Fig. 4 is an enlarged section taken on the line IV-IV of Fig. 1 to show the design of the panes of glass used in a fixture.

We claim:

The ornamental design for a lighting fixture, substantially as shown.

EDWARD E. ASHLEY.
ALEXANDER E. BLUMENTHAL.
